Des. 200,767
Patented Apr. 6, 1965

200,767

SCOOTER

Frank J. Laher, 120 Camino Sobrante, Orinda, Calif.

Filed Mar. 23, 1964, Ser. No. 79,137

Term of patent 14 years

(Cl. D14—3)

FIG. 1

FIG. 2

Des. 200,767

PAGE 2

FIG. 3

FIG. 4

FIG. 5

FIGURE 1 is a perspective view from the right front of a scooter, showing my new design;

FIGURE 2 is a perspective view from the right rear of a scooter shown in FIGURE 1;

FIGURE 3 is a side elevational view of a scooter shown in FIGURE 1;

FIGURE 4 is a top plan view of the scooter shown in FIGURE 1; and

FIGURE 5 is a front elevational view of the scooter shown in FIGURE 1.

The side opposite that shown in FIGURE 3 is a mirror image thereof. It is understood that the cross-hatching shown is continuous throughout the entire area indicated.

I claim:

The ornamental design for a scooter, substantially as shown and described.
